The ornamental design for a control module cooling fan, as shown and described.

DESCRIPTION

FIG. 1 is a front top perspective view of a cooling fan disposed in a control module showing my new design; FIG. 2 is another front top perspective view of the control module of FIG. 1;

FIG. 3 is a front top perspective view of the cooling fan disconnected from the control module of FIG. 1; FIG. 4 is a front elevational view of the control module of FIG. 1;

FIG. 5 is a left side elevational view of the control module of FIG. 1;

FIG. 6 is a right side elevational view of the cooling fan disposed in the control module of FIG. 1;

FIG. 7 is a right side elevational view of the control module of FIG. 1 with the cooling fan removed;

FIG. 8 is a top plan view of the control module of FIG. 1; FIG. 9 is a bottom plan view of the control module of FIG. 1; and,

FIG. 10 is a rear elevational view of the control module of FIG. 1.

The broken lines shown in the drawing views show portions of the article that form no part of the claimed design.
